[57] CLAIM

The ornamental design for an add-on sunvisor, as
shown.

DESCRIPTION

FIG. 1 is a front, top and side perspective view of the
add-on sunvisor showing my new design;

FIG. 2 is a front elevational view thereof, the rear being
a mirror image of the front shown in FIG. 2;

FIG. 3 is an end elevational view thereof;

FIG. 4 is an end elevational view thereof;

FIG. 5 is a top plan view thereof; and,

FIG. 6 is a bottom plan view thereof.

FIG.1.

FIG. 2.

FIG. 5.

FIG. 6.

FIG. 4.

FIG. 3.
